(57) **CLAIM**

I claim the ornamental design for the collapsible measuring cup, as shown and described.

DESCRIPTION

FIG. 1 is a perspective view of the collapsible measuring cup, showing my new design;

FIG. 2 is a top view of the collapsible measuring cup;

FIG. 3 is a front view of the collapsible measuring cup, the back view being a mirror image;

FIG. 4 is a left side view of the collapsible measuring cup;

FIG. 5 is a right side view of the collapsible measuring cup; and,

FIG. 6 is a bottom view of the collapsible measuring cup.

1 Claim, 4 Drawing Sheets
